Primary Examiner — Marianne N Pandozzi

Assistant Examiner — Jae Liang

(57) **CLAIM**

The ornamental design for a mug with enclosure, as shown, and described.

DESCRIPTION

FIG. 1 is a perspective view of a mug with enclosure showing my new design;

FIG. 2 is a left side view thereof, the right side view being a mirror image thereof;

FIG. 3 is a front elevational view thereof;

FIG. 4 is a rear elevational view thereof;

FIG. 5 is a top view thereof; and,

FIG. 6 is a bottom view thereof.

The broken lines in the drawings depict portions of the mug with enclosure that form no part of the claimed design.
